DESIGN FOR A MEMORANDUM PAD HOLDER OR THE LIKE

Joshua Meier, New Rochelle, N. Y.

Application June 30, 1945, Serial No. 120,429

Term of patent 14 years

(Cl. D74—1)

To all whom it may concern:

Be it known that I, Joshua Meier, residing at New Rochelle, in the county of Westchester, State of New York, have invented a certain new, original, and ornamental Design for a Memorandum Pad Holder or the like, of which the following is a specification, reference being had to the accompanying drawing, forming part thereof.

Fig. 1 is a perspective view of the memorandum pad holder showing my new design;

Fig. 2 is a rear perspective view thereof; and Fig. 3 is a top or plan view thereof.

I claim:

The ornamental design for a memorandum pad holder or the like, substantially as shown.

JOSHUA MEIER.
